G. C. PECKHAM.

CAR SEAL.

APPLICATION FILED MAR. 5, 1913.

1,163,554.

Patented Dec. 7, 1915.

UNITED STATES PATENT OFFICE.

GEORGE C. PECKHAM, OF LOS ANGELES, CALIFORNIA, ASSIGNOR TO NATIONAL CAR SEAL COMPANY, OF LOS ANGELES, CALIFORNIA, A CORPORATION OF CALIFORNIA.

CAR-SEAL.

1,163,554.

Specification of Letters Patent.

Patented Dec. 7, 1915.

Application filed March 5, 1913. Serial No. 752,213.

To all whom it may concern:

Be it known that I, GEORGE C. PECKHAM, a citizen of the United States, residing at Los Angeles, in the county of Los Angeles and State of California, have invented new and useful Improvements in Car-Seals, of which the following is a specification.

This invention relates to the type of seals which are used for fastening the door of a car or other closure by passing the seal through the staple or fastening device of the door in such a manner that the door or closure cannot be opened without mutilating the seal, thereby giving evidence if the door has been fraudulently opened.

The invention particularly relates to the class of seals comprising a metal strap which can be readily attached, and when once secured is proof against manipulation without destroying its utility, and one of the main objects of my invention is to produce a seal of the class described in which the entire seal is made from a single strip of metal, and of such simple construction that the seal may be produced at little expense.

A further object of the invention is to provide in such a seal a chambered head having an abutment therein, the head and abutment being formed from the single strip of material and the abutment being in the form of a reverse bend in the chamber with the edges of the abutment locked in the walls of the chamber so that it cannot be withdrawn.

A further object of the invention is to provide means on the abutment for catching and retaining the end of the strap when it is inserted in the chamber.

Referring to the drawings, which are for illustrative purposes only: Figure 1 illustrates the blank from which the seal is made. Fig. 2 shows the blank after having been shaped for assembling. Fig. 3 is a perspective view of the seal in the process of forming. Fig. 4 is a perspective of a portion of the seal in its fastened position, a part of the same being broken away to illustrate the position of the parts in the interior thereof. Fig. 5 is a sectional view of a portion of the seal in its fastened position. Fig. 6 is a perspective view of a portion of

the seal in its fastened position. Fig. 7 is a perspective view similar to Fig. 6, showing the opposite side thereof. Fig. 8 is a sectional view on line x^8-x^9 Fig. 5. Fig. 9 is a sectional view on line x^9-x^9 Fig. 5.

The entire seal, including the head and shackle thereof, is made of a single sheet metal strap or band 1, the blank for the same being shown in Fig. 1. One end of the strap 1 is divided by a transverse bend into a first portion 3, and a second portion 2. When the blank is shaped up by suitable dies, the section 2 is provided with a longitudinally disposed depression at least as wide as the edge of the strap, and which, when the section 3 is bent back on section 2, forms a chamber 4 for receiving the opposite end of the strap, as hereinafter described. Before folding the sections 2 and 3 together, the strap adjacent the inner end of the section 2 is bent into the said section and then back upon itself, as shown in Fig. 3, thereby forming an abutment 5 extending into the chamber 4 of the head 6, as clearly shown in Fig. 5. The abutment 5 is formed by two bends, that portion of the strap lying between the bends being hereinafter called the third portion of the strap, 70 and the main body of the strap being designated as the fourth portion. Previous to bending the strap, as just described, a portion of the same is punched upwardly therefrom to form a catch or tongue 7 which extends away from the strap into the chamber 4. That part of the fourth portion that lies within the chamber and the third portion are provided with longitudinally extending ribs 8 which strengthen the strap 80 and prevent the abutment 5 from being rolled out of the chamber 4 by pulling the strap.

To prevent fraudulent opening of the seal by cutting at the second bend between the second portion 2 and the third portion, which would allow the abutment 5 to be withdrawn and reinserted in the chamber 4 without affecting the external appearance of the chamber, I form a flange 9 on the edges 95 of that part of the fourth portion which is inside the chamber, the flanges 9 being secured in the walls of the chamber as herein-after described.

The chamber 4 is provided with a depression 10 which is formed by pressing the metal of the second portion outwardly therefrom, the depression 10 being arranged 5 to be opposite the catch or tongue 7 to provide clearance therefor when the strap is bent into the form of the abutment 5 within the chamber 4, as heretofore described. The first section 3 is also provided with a 10 longitudinal groove or recess 11 which extends inwardly from the end thereof for receiving a rib or boss 12 which is formed by striking up the metal of the strap adjacent to the end thereof. The end of the 15 strap is provided with an opening 13 punched therein, the walls of which opening 13 are adapted to be engaged by the catch or tongue 7, as hereinafter described.

The section 2 having been formed with 20 the chamber 4 with the depression 10, and the section 3 having been provided with the groove 11, as heretofore described, and the strap adjacent to the section 2 having been bent into the chamber 4 to form the abutment 5 therein, the section 3 is bent back 25 upon the section 2, and the lateral edges or flanges 14 of the section 3 are then bent over the edges or flanges 15 of the section 2 and the flanges 9 on the abutment 5, after which 30 the flanges 14, 15 and the flanges 9 therebetween are crimped for the purpose of locking the same together. By reason of the depression in the section 2 to form the chamber 4, a passage or opening is provided between the section 3 and the adjacent side of 35 the abutment 5 adapted to receive the opposite end of the strap, as hereinafter described.

The free end of the strap is provided with 40 a hook 16 designed to engage or interlock with the hook or abutment 5 in the chamber of the head 6, the hook 16 being formed by bending the end of the strap back upon itself, as shown in Fig. 3. The hook 16 is 45 provided with an abutment designed to be engaged by the tongue or catch 7 which, in the present instance, is the front wall of the aperture or opening 13 through which the tongue or catch 7 passes when the seal is 50 cured.

In using the seal, after the shackle is passed through the staple of the door to be fastened or sealed, the hook end 16 of the strap enters into the head 6 through the passage provided between the hook 5 and the section 3 until the edge of the hook 16 slips off the end of the abutment 5 and expands, due to the resiliency of the metal, after 55 which the strap is pulled outwardly from the head 6, which movement causes the opening 13 in the hook 16 to pass over the catch or tongue 7, in which position the hook 16 will interlock with the abutment 5 and the opening 13 therein will be engaged by 60 the catch or tongue 7, as shown in Figs. 4

and 5, thereby locking the end of the strap against movement in either direction. The catch or tongue 7 being within the head 6, and between the bent over portion of the strap which forms the hook 16, and the part 70 forming the section 2 of the head, it is impossible to reach the same with a tool and disengage the catch from the hook on the end of the strap. As the hook 16 is inserted into the head 6, as above described, 75 and engaged therein by the catch 7, the rib 12 on the end of the strap enters the groove or recess 11 formed in the head 6. The lug or rib 12 is so shaped that the same enters wholly within the groove 11 in the head, 80 leaving exposed to view nothing but the flat portion of the strap extending outwardly from the head. Should an attempt be made to break the band or strap by filing the strap at the point where the same enters the 85 head, the end of the strap could not again be inserted into the head, in view of the fact that the end of the strap would abut against the end 18 of the rib 12, thereby preventing insertion of the same into the head, 90 so that in such case the strap could not be broken or filed, and the same again inserted into the head, in an attempt to make the seal appear intact or untampered with. The crimping of the edges or flanges of the sections 2 and 3 prevents tampering with the seal by bending the same, as the flanges, after having been bent or crimped, as shown, could not be bent so as to open the head without the flanges breaking off, caused by 95 the fracturing of the metal in bending the same after the metal has once been crimped.

What I claim is:

1. A car seal comprising a single metallic strap having a chambered head at one end thereof, an abutment formed within said head by bending said strap upon itself, a hook on the opposite end of the strap from the head, said hook having an opening therein and said hook being so shaped as to engage said abutment, and a catch on the abutment adapted to engage the opening in the hook. 105

2. A car seal comprising a strap having a chambered head formed integrally therewith at one end thereof, said head having an opening at its inner end, an abutment formed by bending the strap upon itself in said head, flanges on said abutment, means for securing said flanges in the walls of the head, a hook on the opposite end of the strap from the head, said hook having an opening therein and said hook being so shaped as to engage said abutment, and a catch on said abutment adapted to engage the opening in said hook. 115

3. A car seal comprising a single metallic strap having a chambered head formed at one end thereof, an abutment formed by bending an intermediate portion of said 120

strap into said head, means for securing the edges of the abutment to the walls of the head, and means on the opposite end of the strap from the head for engaging said abutment.

5 4. A car seal comprising a single metallic strap having a chambered head formed at one end thereof, an abutment formed by bending an intermediate portion of said strap into said head, flanges formed on the edges of said abutment and crimped into the walls of said head, and locking means formed on the other end of said strap from said chambered head, said locking means 10 being adapted to enter said head and engage said abutment.

5 5. In a car seal a combined chamber and abutment formed of a single strap having three bends at one end thereof dividing it 15 into first, second, third, and fourth portions, the second portion having a shallow depression forming the bottom and side walls of the chamber, the third portion being bent 20 back into said depression, the fourth portion being bent in a reverse direction over the third portion thereby forming the abutment, and the first portion forming a cover which is bent over the depression inclosing the abutments, the outer edges of the cover and 25 the abutment being secured to the side walls of the depression.

5 6. In a car seal a combined chamber and abutment formed of a single strap having three bends at one end thereof dividing it 30 into first, second, third, and fourth portions, the second portion having a shallow depression forming the bottom and side walls of the chamber, the side walls having flanges 35 parallel to the bottom, the third portion being bent back into said depression, the fourth portion being bent in a reverse direction over the third portion thereby forming the abutment, and the first portion forming a cover which is bent over the depression, 40 the edges of the cover being crimped over the said flanges and the edges of the abutment.

5 7. In a car seal a combined chamber and abutment formed of a single strap having 45 three bends at one end thereof dividing it into first, second, third, and fourth portions, the second portion having a shallow depression forming the bottom and side walls of the chamber, the third portion being bent 50 back into said depression, the fourth portion being bent in a reverse direction over the third portion thereby forming the abutment, and the first portion forming a cover which is bent over the depression inclosing 55 the abutment, the outer edges of the cover and the abutment being secured to the side walls of the depression, said combined chamber and abutment being formed on one end of the strap and the other 60 end of the strap having a single bend forming a hook so shaped that it can pass into 65 said chamber and engage said abutment, having a single bend forming a hook so

shaped that it can pass into said chamber and engage said abutment.

8. In a car seal a combined chamber and abutment formed of a single strap having three bends at one end thereof dividing it 70 into first, second, third, and fourth portions, the second portion having a shallow depression forming the bottom and side walls of the chamber, the side walls having flanges parallel to the bottom, the third portion being bent back into said depression, the fourth portion being bent in a reverse direction over the third portion thereby forming the abutment, and the first portion forming a cover which is bent over the depression, 75 the edges of the cover being crimped over the said flanges and the edges of the abutment, said combined chamber and abutment being formed on one end of the strap and the other end of the strap having a single bend forming a hook so shaped that it can pass into said chamber and engage said abutment.

9. In a car seal a combined chamber and abutment formed of a single strap having 80 three bends at one end thereof dividing it into first, second, third, and fourth portions, the second portion having a shallow depression forming the bottom and side walls of the chamber, the third portion being bent 85 back into said depression, a part of said third portion being punched out to form a tongue extending away from said abutment, the fourth portion being bent in a reverse direction over the third portion thereby forming the abutment, and the first portion forming a cover which is bent over the depression inclosing the abutment, the outer edges of the cover and the abutment being secured to the side walls of the depression, 90 said combined chamber and abutment being formed on one end of the strap and the other end of the strap having a single bend forming a hook so shaped that it can pass into 95 said chamber and engage said abutment, said hook having an opening so placed as to be engaged by said tongue.

10. In a car seal a combined chamber and abutment formed of a single strap having three bends at one end thereof dividing it 115 into first, second, third, and fourth portions, the second portion having a shallow depression forming the bottom and side walls of the chamber, the side walls having flanges 120 parallel to the bottom, the third portion being bent back into said depression, a part of said third portion being punched out to form a tongue extending away from said abutment, the fourth portion being bent in a reverse direction over the third portion thereby forming the abutment, and the first portion forming a cover which is bent over the depression, 125 the edges of the cover being crimped over the said flanges and the edges of the abutment, said combined chamber and 130

abutment being formed on one end of the strap and the other end of the strap having a single bend forming a hook so shaped that it can pass into said chamber and engage said abutment, said hook having an opening so placed as to be engaged by said tongue.

Copies of this patent may be obtained for five cents each, by addressing the "Commissioner of Patents, Washington, D. C."

In testimony whereof, I have hereunto set my hand at Los Angeles, California, this 26th day of February, 1913.

GEORGE C. PECKHAM.

In presence of—

FRANK L. A. GRAHAM,
P. H. SHELTON.
